UNITED STATES PATENT OFFICE.

ELMER F. MACKUSICK, OF NEW YORK, N. Y., ASSIGNOR OF ONE-HALF TO
GEORGE VICKERY FOSTER, OF NEW YORK, N. Y.

GAS-HOLDER.

SPECIFICATION forming part of Letters Patent No. 693,292, dated February 11, 1902.

Application filed August 28, 1900. Serial No. 28,291. (No model.)

To all whom it may concern:

Be it known that I, ELMER F. MACKUSICK, a citizen of the United States, and a resident of the city of New York, borough of Manhattan, 5 in the county and State of New York, have invented a new and Improved Gas-Holder for Acetylene-Gas Generators, of which the following is a full, clear, and exact description.

The object of the invention is to provide a 10 new and improved gas-holder for acetylene-gas generators arranged to cool the gas to insure a rapid condensation of the moisture in the gas, so that it will pass to the bell in a dry state.

15 It also has for its object to provide means for the escape of the gas in case of excessive pressure accumulating in the gas-chamber in the upper part of the water-tank of the holder.

The invention consists of novel features 20 and parts and combinations of the same, as will be fully described hereinafter and then pointed out in the claims.

A practical embodiment of the invention is represented in the accompanying drawings, 25 forming a part of this specification, in which similar characters of reference indicate corresponding parts in all the views.

Figure 1 is an enlarged plan view of the same with parts in section. Fig. 2 is a transverse section of the same on the line 2 2 in Fig. 1. Fig. 3 is a sectional side elevation of the same on the line 3 3 in Fig. 1. Fig. 4 is an enlarged perspective view of part of the partition for forming the vertical channels of 35 the condenser. Fig. 5 is an unrolled view of a portion of the same, and Fig. 6 is a perspective view of the pipe arrangement for the escape of the excessive pressure of gas and the water of condensation.

40 In the drawings, A is a tank adapted to contain water, and in the said tank is arranged to rise and fall a gas-bell B, preferably having on opposite sides a downwardly-extending box B' for containing removable weights B² for giving the desired pressure to the gas accumulating in the bell and also for giving the necessary stability to the bell.

45 In the tank A, a suitable distance from the bottom thereof, is arranged an inclined plat- 50 form or support C, adapted to support a plurality of charges of calcium carbid or other

generating substance, the charges being held on the platform by the retaining device D. The charges are fed from the inclined guide-way E to said platform through an upwardly-extending passage F, leading to the top of the tank A at one side thereof and outside of the tank and the bell, said passage being in communication with the interior of the tank, so that it is filled to the same level with water 60 as the tank itself. The inlet to the passage F is controlled by a cut-off valve G, carried by the bell. The lower side of the support C opens into a well H, likewise filled with water to the level of that in the tank and arranged 65 on the outside thereof, and in this well is arranged a carrier in the form of a basket H', adapted to receive the spent charges from the support C and connected by ropes or chains i with a windlass J, so that the spent charges 70 can be raised to the top of the well.

Within the tank A and concentric with the inner surface thereof is arranged an annular condensing-chamber O, forming with the wall of the tank an annular space for the passage 75 of the bell B, the lower end of said chamber O being attached by an annular bracket O' to the wall of the tank A. (See Fig. 2.) A hollow cover M, having bevel sides N, is secured to the upper end of the condensing- 80 chamber O, so as to form therewith an annular chamber L, into which the gas deflected outward by the cone-shaped deflector K passes. The chamber O is formed with vertically-disposed channels P, alternately connected with each other by the top and bottom, one channel P' opening at its upper end by a port P² (see Figs. 1 and 3) into the annular chamber L, so that the generated gas can pass from this chamber L into and 85 through the several connected channels P, and consequently up and down all around in the annular chamber O, exposed to the cooling action of the water in the tank A to insure a rapid condensation of the moisture in 90 the gas, so that the latter passes in a perfectly dry state through the open top of the channel P³ (see Fig. 1) into the bell B to accumulate therein and to pass from the bell to the channel P⁴, arranged between the channels P' and P³, (see Fig. 1,) but not in communication therewith. The gas flows down- 95 100

ward through the channel P^4 to the lower end thereof, and this lower end connects with a pipe Q , extending first downwardly below the chamber O and then forwardly to rise outside 5 of the tank A in one of the corners formed by the tank and the well H , as is plainly shown in Fig. 1, the rising end Q' of the pipe Q leading the gas to the burners for consumption. The channels P are formed by partitions arranged at angles to one another, (see Figs. 1 and 4,) V-shaped notches P^5 P^6 being alternately arranged on the upper and lower ends of successive partitions. (See Fig. 5.) The partitions for the top notches P^5 have their 10 lower ends P^7 extended downward beyond the notches P^6 to the bottom of the condensing-chamber O , and these extended ends P^7 have their bottoms cut out to allow the water of condensation from the several channels P to 15 accumulate in the bottom of said chamber O and finally flow through the gas-outlet pipe Q into a drip-pipe Q^2 , extending from said pipe Q downwardly and transversely and terminating in a rising end Q^3 , discharging into 20 a pail or other receptacle Q^4 set in a recess in the tank below the passage F , as is plainly shown in Fig. 2. Water stands in the chamber O up to the bottom of the outlet-pipe Q , and said outlet-pipe is slightly above the level 25 of the lower ends of the partitions having the notches P^6 . (See Figs. 3 and 5.) By the arrangement described the lower ends P^7 of the partitions are water-sealed, so that the generated gas has to travel up and down the 30 channels P before escaping through to the channel P^8 into the bell B and without the gas passing directly to the channel P^4 and pipe Q .

In order to maintain an approximately constant water-level in the tank A , the passage 40 F , and the well H , a water-supply pipe R is provided, opening into the well at one corner thereof, as is plainly shown in Fig. 1, and on the inner end of this water-supply pipe R is arranged a valve R' , controlled by a float R^2 , 45 which opens the valve when the water falls and closes the valve when a sufficient quantity of water has been supplied to maintain a normal level in the tank A , the passage F , and the well H .

50 The internal cover M , previously referred to, for the tank A is made hollow and formed in its bottom with a downwardly-extending tube N^2 , opening at its lower end below the top of the cone-shaped deflector K , as plainly indicated in Figs. 2 and 3. Into the cover M extends a pipe S , forming a support for the deflector K and extending downwardly and then to one side and again downwardly and forwardly to the outside of the tank A , finally 55 terminating in an upwardly-extending discharge-pipe S' opening into the outer air, said pipe S' passing upwardly in the well H , as is plainly shown in Fig. 1. The pipes S S' form an escape in case of excessive pressure 60 of gas accumulating in the annular chamber L , it being understood that by such excessive pressure the water in the tank A is forced

downward, and when the pipe N^2 is uncovered the gas can pass through the pipe N^2 into the hollow cover M and then through the pipes S S' to the outer air. The principal object of the deflector K is to act as a safety blow-off in case of excessive pressure, as the gas is positively caused to pass into the cover M and by way of pipe S to the outside. By 70 reference to Figs. 2 and 3 it will be seen that the top edge of the cone-shaped deflector K extends a suitable distance below the bottom of the cover M , so that when excessive generation of gas forces the water downward in 75 the tank A then a small amount of water is retained in the deflector K and a portion of said water is forced up through the pipe N^2 into the cover M to finally pass through the pipe S out of the cover, as above explained. 80 Thus by the arrangement described but a small quantity of water can pass through the cover M and pipe S out of the tank in case of 85 excessive pressure, and since the force required to cause the water to flow up into the 90 cover decreases, owing to the shape of the deflector, while the pressure on the water in the tank A must necessarily increase to force it out of the bell into the tank, a blow-off through cover M and pipe S takes place before the gas 95 can possibly blow off at the lower end of the bell.

The generator herein shown and described forms no part of the present application, being made the subject of a separate application, Serial No. 51,075, filed March 14, 1901.

Having thus described my invention, what I claim as new, and desire to secure by Letters Patent, is—

1. A gas-holder having a gas-bell, a water-tank having two concentric chambers into the outer one of which the bell extends, a hollow cover for the inner chamber and opening into the same below the normal water-line thereof, a gas communication between the chambers and an escape or safety pipe leading from the interior of said cover to the outside, as set forth.

2. A gas-holder having a gas-bell, a water-tank having two concentric chambers into the outer one of which the bell extends, a hollow cover for the inner chamber and opening into the same below the normal water-line thereof, a gas communication between the chambers, an escape or safety pipe leading from the interior of said cover to the outside, and a cone-shaped deflector below the opening of the said cover, as set forth.

3. A gas-holder provided with a water-tank having two concentric chambers, a gas-bell arranged to rise and fall in the outer chamber, a cover for the inner chamber and forming therewith a gas-chamber in the upper part of the same, said cover being independent of the bell, and a condensation-chamber arranged between the chambers of the water-tank, and having an annularly-arranged circuitous conduit opening at one end into the gas-chamber adjacent to the cover and at its

other end into the bell, both the inlet and outlet of the condensing-chamber being at the top of the same, as set forth.

4. A gas-holder provided with a water-tank having two concentric chambers, a gas-bell arranged to rise and fall in the outer chamber, a cover for the inner chamber and forming therewith a gas-chamber in the upper part of the same, said cover being independent of the bell, and a condensation-chamber arranged between the concentric chambers and having an annularly-arranged circuitous conduit opening at one end into the gas-chamber adjacent to the cover, and at its other end into the bell, both the inlet and outlet of the condensing-chamber being at the top of the same, and a discharge-passage between the inlet and outlet of the conduit and opening at one end into the bell and connecting at its other end with the gas-supply, as set forth.

5. A gas-holder provided with a water-tank having two concentric chambers, a gas-bell arranged to rise and fall in the outer chamber, a cover for the inner chamber and forming in the upper part thereof a gas-chamber, said cover being independent of the bell, and a condensation-chamber arranged between the said concentric chambers and having a circuitous conduit opening at one end into the gas-chamber and at its other end into the bell, said conduit being formed by a series of vertical channels connected with each other alternately at top and bottom, as set forth.

6. A gas-holder provided with a water-tank having two concentric chambers, a gas-bell arranged to rise and fall in the outer chamber of the tank, a cover for the inner chamber and forming therewith a gas-chamber, said cover being independent of the bell, an annular condensation-chamber arranged between the said chambers and having a circuitous conduit opening at one end into the gas-chamber, and at its other end into the bell, said conduit being formed by a series of annularly-arranged vertical channels connected with each other alternately at top and bottom, and means for carrying off the water of condensation from the condensation-chamber, as set forth.

50 7. A gas-holder provided with a water-tank having two concentric chambers, a cover for the inner chamber and forming in the upper part thereof a gas-chamber, a gas-bell arranged to rise and fall in the outer chamber, and an annular condensing-chamber between the two chambers of the tank and having a continuous channel opening at one end into the said chamber and at the other end into the bell, said channel being formed by partitions arranged at angles to one another and formed with notches alternately at their upper and lower ends, as set forth.

8. A gas-holder provided with a water-tank having two concentric chambers, a cover for the inner chamber, said cover having beveled sides and forming in the upper part of the said inner chamber a gas-chamber, a gas-bell

arranged to rise and fall in the outer chamber, and an annular condensing-chamber provided with a series of vertical partitions arranged at angles to one another and formed with notches alternately at their upper and lower ends, said partitions forming a continuous channel which opens at one end into the said gas-chamber and at its other end into the bell, as set forth. 70 75

9. A gas-holder provided with a water-tank having two concentric chambers, a cover for the inner chamber and forming therewith a gas-chamber, a bell arranged to rise and fall in the outer chamber, and an annular condensing-chamber arranged between the said chambers and provided with a series of vertical partitions arranged at angles to one another and formed with notches alternately at 85 their upper and lower ends, said partitions forming a continuous circuitous channel which opens at one end into the gas-chamber and at its other end into the bell, and a discharge-passage arranged between the inlet 90 and outlet of the channel and opening at one end into the bell and connected at its other end with the gas-supply for the burners, as set forth.

10. A gas-holder having a water-tank, a bell, 95 an annular condensation-chamber secured to the tank at the inside and spaced from the wall of the same so as to divide the tank into two portions, and a hollow cover having an inclined side secured to the condensation-chamber to close the inner portion of the tank and to form with the said chamber a gas-receiving chamber opening into the same, substantially as shown and described. 100

11. A gas-holder having a water-tank, a bell, 105 an annular condensation-chamber secured to the tank at the inside and spaced from the wall of the same, a hollow cover having an inclined side secured to the condensation-chamber to close the inner portion of the tank 110 and to form with the said chamber a gas-receiving chamber opening into the same, said cover having in its bottom a downwardly-extending pipe, and an air-pipe leading from the interior of the cover through the said pipe to 115 the outer air as set forth.

12. A gas-holder having a water-tank, a bell, an annular condensation-chamber secured to the tank at the inside and spaced from the wall of the same, a hollow cover having an 120 inclined side secured to the condensation-chamber to close the inner portion of the tank and to form with the said chamber a gas-receiving chamber opening into the same, said cover having in its bottom a downwardly-extending pipe, a cone-shaped deflector below 125 the cover and into which opens the pipe of said cover, and an air-pipe leading from the interior of said cover through its pipe to the outer air, as set forth. 130

13. A gas-holder having a water-tank, a bell, an annular condensation-chamber secured to the tank at the inside and spaced from the wall of the same, a hollow cover having an

inclined side secured to the condensation-chamber to close the inner portion of the tank, and to form with the said chamber a gas-receiving chamber opening into the same, said 5 cover having in its bottom a downwardly-extending pipe, a cone-shaped deflector below the cover and into which opens the pipe of said cover, and an air-pipe leading from the interior of said cover through its pipe to the

outer air, said air-pipe forming a support for the said deflector, as set forth.

In testimony whereof I have signed my name to this specification in the presence of two subscribing witnesses.

ELMER F. MACKUSICK.
